UNITED STATES PATENT OFFICE.

THEODORE B. ROWELL, OF BEAVER DAM, WISCONSIN, ASSIGNOR TO THOMAS S. ROBERTS, OF EVANSTON, ILLINOIS.

DISK-DRILL SEEDING-MACHINE.

1,087,320.

Specification of Letters Patent.

Patented Feb. 17, 1914.

Application filed August 25, 1913. Serial No. 736,436.

To all whom it may concern:

Be it known that I, THEODORE B. ROWELL, a citizen of the United States, and resident of Beaver Dam, in the county of Dodge and 5 State of Wisconsin, have invented certain new and useful Improvements in Disk-Drill Seeding-Machines; and I do hereby declare that the following is a full, clear, and exact description thereof.

10 My invention consists in what is herein particularly set forth with reference to the accompanying drawings and pointed out in the claims of this specification, its principal objects being exclusion of dust from between the stationary hubs and revolving disks of disk-drill seeding machines, and to prevent slipping of said hubs in their supports.

Figure 1 of the drawings represents a 20 sectional view of a fragment of a disk-drill seeder, the plane of the section being indicated by line 1—1 in Figs. 2 and 3; Fig. 2, a side elevation of the same partly in section on the plane indicated by line 2—2 in Fig. 1; Fig. 3, a similar view partly in section on the plane indicated by line 3—3 in Fig. 1, and Fig. 4, a detail section indicated by line 4—4 in Fig. 3.

Referring by numerals to the drawings, 30 5 indicates a fragment of a boot of a disk-drill seeding machine and 6 an arm of the same, this arm being provided with an angular opening engaged by a matching angular reduced projection 7 of a hub 8. Opposite sides of the hub are slabbed for a portion of its length to have angular fit in a dust-cap 9, facing shoulders 8' of said hub that result from the slabbing of the same. Slipped on the hub against a circular and 40 dished flange 10 of the same is a furrow-opening disk 11 that faces the dust-cap 9 and is free to revolve, and a carriage-bolt 12 engaging said hub extends beyond the same through a washer 13 and a nut 14, the 45 washer being opposed to the boot-arm aforesaid. However it is within the scope of my invention, as herein claimed, to adapt the boot-arm to the employment of a pair of disks, in which case the bolt will be sufficiently long to extend through the hubs of both disks similar to what is customary practice in the art to which my invention relates.

A spiral-spring 15 is arranged under tension between the boot-arm 6 and a flange 9'

of the cap 9, said flange being annularly grooved to engage the spring by which said cap is held on the hub 8 tight against the disk 11 to exclude dust from between said hub and said disk. Bolted on the other side 60 of the disk is the usual flanged cap 16 that incloses the flanged end of the hub and has a central opening closed by a flanged screw-plug 17, this opening being provided to permit of access to the head of the bolt 12 65 aforesaid.

The boot-arm 6 is provided with side seats 18 for the studs 9' of the hub, these seats being in opposite series to provide for forward adjustment of a worn disk subsequent 70 to the removal of some or all of a thin web 18' of said arm. The studs engaging a pair of the seats therefor prevent the hub from slipping in the angular opening of the boot-arm with which it is engaged. 75

I claim:

1. The combination in a disk-drill seeding machine of a flanged hub having an angular projection, slabbed sides and angular shoulders; a disk loose on the hub in opposition to the flange thereof, a flanged dust-cap having slip-fit on the slabbed portion of the hub against the disk and opposite the hub-shoulders, a support in which the angular projection of the hub has 80 match-fit, means for securing the hub in connection with the support, and a spiral-spring under tension between said support and the dust-cap flange. 85

2. The combination in a disk-drill seeding machine of a flanged hub having an angular projection, slabbed sides and angular shoulders; a disk loose on the hub in opposition to the flange thereof, a grooved flanged dust-cap having slip-fit on the 90 slabbed portion of the hub and provided with inwardly extending angular lugs facing the hub-shoulders, a support in which the angular projection of the hub has match fit, means for securing the hub in connection 95 with the support, and a spiral-spring seated in the flange-groove of the dust cap under tension between it and said support. 100

3. The combination in a disk-drill seeding machine of a flanged hub having a reduced angular projection and diametrically opposite forward studs, a disk loose on the hub in opposition to the flange thereof, a support in which the angular projection of the hub has match-fit and which is provided 105 110

with side seats for the hub-studs, and means for securing said hub in connection with the support.

4. The combination in a disk-drill seed-
3 ing machine of a flanged hub having a re-
duced angular projection and diametrically
opposite forward studs, a disk loose on the
hub in opposition to the flange thereof, a
support in which the angular projection of
10 the hub has match-fit adjacent to a web
thereof, the support being provided with a
plurality of side seats for each hub-stud to
provide for adjustment of said hub upon re-
moval of some or all of said web; and means
15 for securing said hub in connection with
said support.

5. The combination in a disk-drill seed-
ing machine of a flanged hub having a re-

duced angular projection and diametrically
opposite forward studs, a disk loose on the 20
hub in opposition to the flange thereof,
means for excluding dust from between the
hub and disk, a support in which the angu-
lar projection of the hub has match-fit and
which is provided with side seats for the 25
hub-studs, and means for securing said hub
in connection with the support.

In testimony that I claim the foregoing I
have hereunto set my hand at Beaver Dam
in the county of Dodge and State of Wis- 30
consin in the presence of two witnesses.

THEO. B. ROWELL.

Witnesses:

J. F. MALONE,
IRA B. LUTHER.
